UNITED STATES PATENT OFFICE.

JAMES S. DONNELLAN, OF DUBUQUE, IOWA.

OIL-CUP FEEDER.

SPECIFICATION forming part of Letters Patent No. 447,300, dated March 3, 1891.

Application filed August 12, 1890. Serial No. 361,807. (No model.)

To all whom it may concern:

Be it known that I, JAMES S. DONNELLAN, a citizen of the United States, residing at Dubuque, in the county of Dubuque and State of Iowa, have invented a new and useful Oil-Cup Feeder, of which the following is a specification.

This invention relates to oil-cup feeders, and is in the nature of a device adapted to be applied to ordinary oil-cups or lubricators for machinery for the purpose of conveying the lubricating material to the bearings; and it has for its object to construct a feeding device in the nature of a wick in such a manner that the flow of the lubricating material may be regulated according to the season of the year and to the more or less heated state of the bearings when the lubricating material is in a more or less liquid state.

20 The invention consists in a compound wick made of wire and of worsted or other yarn, in the manner and for the purpose which will be hereinafter fully described, and particularly pointed out in the claims.

25 In the drawings, Figure 1 is a vertical sectional view of an oil-cup equipped with a feeder constructed according to my invention. Fig. 2 is a perspective detail view showing the feeder detached and with parts broken away to more clearly illustrate the invention. Fig. 3 is a transverse sectional view taken on the line 3 3 in Fig. 1.

Like numerals of reference indicate like parts in all the figures.

35 1 designates an oil-cup, which is of ordinary construction and for which no special novelty is herein claimed, said oil-cup being composed of the base 2, having a screw-threaded nipple 3, the cup or glass 4, the top 40 5, and the cover or plug 6.

7 designates my improved feeder, which is composed of a core 8 of wire, which is twisted so as to form at the ends thereof the loops 9. Suitably attached to the said core are a 45 series of strands 10 of worsted or other yarn. Part or all of these strands are permitted to project through the loop 9 at one end of the wire core, said strands being preferably

threaded through the eye or loop at the opposite end of the core and doubled over the 50 latter and secured. In this manner a series of ends (designated by 11) are caused to project from the loop at one end of the core. In the loop at the opposite end is tied a single strand of yarn, thus forming two projecting 55 ends, (designated by 12.)

A portion of my invention is dependent upon the fact that while at one end of the core a number of the ends of the yarn exceeding two are permitted to project, at the 60 opposite end only two such yarn ends and no more are permitted to project. This may be modified to the extent that an unequal number of strands without regard to the actual number shall be permitted to project at 65 opposite ends of the core.

The operation of my invention will be readily understood. The feeder is introduced vertically through the lubricator or oil-cup, and one end of the same is caused to enter 70 the nipple at the lower end of the cup. When the end of the feeder having the larger number of projecting ends is thus introduced, the said strands will be folded up within the nipple, and will thus serve to partially check the 75 flow of the lubricating material. If it shall be desired to increase the flow, the feeder may be simply reversed and the end having the less number of projecting strands be introduced into the nipple, the capacity of which 80 for the passage of lubricating material will thus be increased.

Having thus described my invention, what I claim, and desire to secure by Letters Patent of the United States, is—

85 1. A wire core twisted to form loops or eyes at opposite ends thereof, in combination with a covering of yarn threaded through said loops, substantially as set forth.

2. A core provided with loops or eyes at 90 its ends, in combination with a covering of yarn having ends projecting at one end of said core and a single strand of yarn tied in the eye at the opposite end of said core, substantially as set forth.

95 3. The combination, with a lubricator or

oil-cup, of a reversible feeder and regulator consisting of a wire core having eyes or loops at its ends, a covering of yarn threaded through said eyes, and an unequal number of 5 strands of yarn projecting at opposite ends, substantially as and for the purpose set forth.

In testimony that I claim the foregoing as

my own I have hereto affixed my signature in presence of two witnesses.

JAMES S. DONNELLAN.
